BERNT OLSEN, OF MINNEAPOLIS, MINNESOTA, AND ONE-FOURTH TO HOWARD L.
PEDERSON, OF ANOKA, MINNESOTA.

WIND AND WATER MOTOR.

Application filed July 10, 1926. Serial No. 121,703.

This invention relates to a wind or water motor and particularly to such a motor of large size adapted to be placed in an elevated position in the wind or to be placed 5 in the water of a stream.

It is an object of this invention to provide a wind or water motor comprising a large wheel having end plates and a plurality of vanes extending longitudinally therebetween, which vanes are trough-shaped and substantially crescent-shaped in cross section.

It is a further object of the invention to provide an air or water motor with such a 15 wheel as set forth in the preceding paragraph, which wheel is axially journaled in a frame which is revoluble about a central vertical axis, a casing being provided about said frame having a plurality of sides which 20 are equipped with vertically slidable portions adapted to be disposed at various heights.

It is still another object of the invention to provide an air motor adapted to be carried 25 on a tower having a platform on which a frame is revolvably mounted, which frame has standards at opposite ends in which is journaled a wheel having end plates and a plurality of trough-shaped vanes extending 30 therebetween, said frame being revoluble about a vertical shaft disposed centrally thereof and extending through the platform, said shaft being connected by suitable gearings so as to be rotated by the revolution of 35 said wheel, said platform having a plurality of vertically extensible sides thereabout which can be raised to and held at various heights.

These and other objects and advantages 40 of the invention will be fully set forth in the following description made in connection with the accompanying drawings, in which like reference characters refer to similar parts throughout the several views and 45 in which:

Fig. 1 is a view partly in vertical section and partly in front elevation of applicant's device;

Fig. 2 is a vertical section taken on line 50 2-2 of Fig. 1, as indicated by the arrows;

Fig. 3 is a horizontal section taken on line 55 3-3 of Fig. 2 as indicated by the arrows; and

Fig. 4 is a partial view similar to Fig. 2, showing the wheel disposed in the current 55 of a stream.

Referring to the drawings, an air motor is shown comprising a tower which will be of considerable height and which has a platform 6 at its top which is supported upon a suitable number of legs 7. A frame 8 is provided having journaled thereon adjacent its bottom a plurality of circumferentially spaced rollers 9 resting upon the platform 6 and by means of which said frame is rev- 65 olubly supported upon said platform. The frame 8 has at opposite ends vertically extending standards 8^a having bearings at their upper ends in which are journaled the trunnions 10^a of the wind wheel 10. The 70 wheel 10 comprises end plates 10^b between which extend a plurality of vanes 10^c. While these vanes may be made in various forms, in the embodiment of the invention illustrated they are shown as trough-shaped 75 or substantially crescent-shaped in cross section. A bracket 11 is secured at the outer end of one of the standards 8^a having an upper bearing through which one trunnion 10^a of the wheel 10 projects, which trunnion 80 has secured thereto a beveled gear 12. The gear 12 meshes with another beveled gear 13 secured to the upper end of shaft 14 journaled in a bearing carried by bracket 11, said gear 13 resting on said bracket. Another 85 bracket 15 is secured adjacent the bottom of said standard 8^a also having vertical and horizontal bearings disposed at right angles to each other in the vertical bearing of which the lower end of shaft 14 is journaled, said 90 shaft having a beveled gear 16 secured to its lower end. The gear 16 meshes with beveled gear 17 carried on the outer end of shaft 18 which is journaled in the horizontal bearing of bracket 15 and in a small bearing 19 secured on the frame 8. The shaft 18 has a beveled gear 20 secured to its inner end which meshes with another beveled gear 21 secured to the upper end of a vertical shaft 22. Shaft 22 extends downward through frame 8 and the platform 6 and the power and motion developed by the wind wheel 10 are transmitted to the shaft. The shaft 22 has a collar 23 secured thereto at some distance below the platform 6 and a beveled gear 24 journaled at shaft 22 rests 95

100

105

upon said collar. The gear 24 carries a sleeve extending from its upper end through a bearing secured to the lower side of platform 6 and through the bearing plate 26 secured to the upper side of platform 6, said sleeve being secured at its upper end to a bearing plate 27 which is in turn secured to the bottom of the frame 8. If desired, suitable anti-friction bearings may be disposed between the plates 26 and 27. A beveled gear 28 meshes with gear 24 and is carried on one end of the shaft 29 journaled in a bearing 30 secured to the lower side of platform 6. The gear 28 bears against one side of bearing 30 and the shaft 29 is held in position by a collar 31 secured thereto and engaging the other side of bearing 30. The shaft 29 also has secured thereto a sheave or pulley 32 over which runs a rope 33 which will extend downward to a point convenient for manipulation by the operator. With the described structure, when the rope 31 is operated, gears 28 and 24 will be rotated and frame 8 will be rotated by means 25 of the sleeve extending from gear 24 and secured to said frame.

The platform 6 has a plurality of sides 34 disposed thereabout and in the embodiment of the invention illustrated four of such sides are shown. The sides 34 extend to a point substantially in horizontal alignment with the axis of the trunnions 10^a of the wheel 10. The sides 34 are secured to posts 35 disposed at the corners of the platform 6 and said posts have grooves or guideways in which are slidably mounted vertically movable side members or extensions 36. The members 36 have secured adjacent their lower ends the ends of the ropes or cables 37 which extend over pulleys 38 mounted in brackets 39 secured adjacent the tops of the sides 34 and said ropes 37 then extend downward through the platform 6 to a point which will be convenient for manipulation of said ropes by the operator.

In operation the tower comprising the members 7 will be of suitable height and disposed in a suitable place so that the wind will have free access to the wheel 10. When it is desired to operate the wheel the frame 8 will be turned so that the longitudinal axis of the wheel is substantially at right angles to the direction of the wind. The frame 8 can be turned by pulling upon the ropes 33 which action, as stated, will through gears 28 and 24 rotate the frame 8. The ropes 33 will then be secured so that the frame is held in the desired position. The wind blowing in the direction indicated by the arrows 40 will now actuate the wheel 10 which will rotate in the direction indicated by the arrow 41 in Fig. 2. It will be seen that the wind can only effectively engage the upper half of the wheel and is prevented from blowing against the lower half of the

wheel by the sides 34. The wheel is thus very effectively disposed in relation to the wind and the rotation of the wheel 10 will rotate the gear 12 which will, through gears 13 and 16 and shaft 14, rotate the gear 17. 70 This will in turn rotate the shaft 18 and the latter will through the gears 20 and 21 rotate the shaft 22. The shaft 22 will extend downward to a suitable point and will be connected to the desired machinery or power 75 generating units.

If the wind should drive the wheel 10 at a speed above that desired, the operator, by manipulating ropes 37, will raise the sides 36 so that the wind can only strike the upper portion of the wheel 10. The speed of the wheel 10 will thus be controlled. If it is not desired to operate the wheel 10, the sides 36 can be raised to the limit of their vertical movement and wheel 10 will thus be effectively shielded from the wind. 85

In Fig. 4 the wheel 10 is shown as having its lower side submerged in the water of the stream or current 42 flowing in the direction of the arrows 43. The wheel will thus be rotated in the direction indicated by the arrow 44. The wheel will be mounted so that it can be submerged more or less in the current and the power generated by the wheel thus controlled. 90

From the above description it is seen that the applicant has provided a very simple and efficient air or water motor. The power generating wheel is mounted so that it can be brought into the proper position in the wind and means are provided for controlling the action of the wind thereon. As stated, the wheel will be made quite large and a very simple and efficient power generating device is thus provided. It is well known that in some portions of the country the wind blows almost constantly and by the use of applicant's device the power of the wind can be easily and effectively utilized. Applicant's device can, of course, be used 100 to drive a generator or to operate a pump to pump air or other fluid into a tank which can then be used as desired. The device has been demonstrated in actual practice and found to be very successful. 110

It will, of course, be understood that various changes may be made in the form, details, arrangement and proportions of the parts, without departing from the scope of applicant's invention, which, generally stated, consists in a device capable of carrying out the objects above set forth, in the novel parts and combinations of parts disclosed and defined in the appended claims. 115

What is claimed is:—

1. A wind motor having in combination, a wheel having a plurality of substantially radially extending vanes, a casing surrounding said wheel having rigid permanent walls extending substantially the height of the 130

axis of said wheel, a frame on which said wheel is revolvably mounted disposed within said casing, said frame being revolvable about its central axis whereby said wheel may be 5 rotated to bring said vanes into position at right angles to the direction of the wind.

2. A wind motor having in combination, a wheel having a plurality of substantially radially extending vanes, a fixed casing surrounding said wheel having rigid fixed walls extending substantially to the height of the 10 axis of the wheel, and vertically movable sections at each side of said wheel adapted

to be raised different distances above said wall and held in various positions to shield 15 more or less of said wheel from the wind, a shaft extending vertically from the bottom of said casing, a support for said wheel revolvable about the axis of said shaft whereby said wheel may be rotated about said axis 20 in said casing, and a driving means mounted on said support actuated by rotation of said wheel and connected to said shaft to drive the same.

In testimony whereof I affix my signature.

AUGUST ERICKSON.
